UNITED STATES PATENT OFFICE

161,933

INFANT CHAIR TRAINER

Byron T. Jack Vance, Hollywood, Calif.

Application February 21, 1949, Serial No. 994

Term of patent 14 years

(Cl. D4—5)

To all whom it may concern:

Be it known that I, Byron T. Jack Vance, a citizen of the United States, residing in Hollywood, in the county of Los Angeles, State of California, have invented a new, original, and ornamental Design for an Infant Chair Trainer, of which the following is a specification, reference being had to the accompanying drawing, forming a part thereof.

Figure 1 is a front elevational view of an infant chair trainer, showing my new design.

Figure 2 is a side elevational view.

Figure 3 is a plan view.

I claim:

The ornamental design for an infant chair trainer, substantially as shown.

BYRON T. JACK VANCE.
